UNITED STATES PATENT OFFICE.

ENNIS E. SHERRILL, OF DALHART, TEXAS.

HOT-BOX COOLER.

Application filed February 24, 1923. Serial No. 621,103.

To all whom it may concern:

Be it known that ENNIS E. SHERRILL, citizen of the United States, residing at Dalhart, in the county of Dallam and State of Texas, has invented certain new and useful Improvements in Hot-Box Coolers, of which the following is a specification.

This invention relates to a hot box cooler for the journals and journal boxes of rail-10 way cars and it has for its object to provide a device of this character constructed in such manner as to discharge a stream of water upon a heated journal during the transit of the car.

15 It is a further object of the invention to so support the reservoir containing the cooling water that it will be maintained in a warm condition by the heated journal box and journal and will thereby be prevented from 20 freezing in cold weather.

Further objects and advantages of the invention will be set forth in the detailed description which follows.

In the accompanying drawing:

25 Fig. 1 is a view partly in side elevation and partly in section of a journal box constructed in accordance with the invention; and

Fig. 2 is a plan view thereof.

30 Like numerals designate corresponding parts in both of the figures of the drawing.

The device of the present invention comprises a bucket like receptacle 5 having a carrying bail and hinged closure plate 7 and 35 8. This receptacle is adapted to be held in position within the mouth of a journal box 9 by means of a chain 10 which extends around the receptacle and is connected to a ring 11. This ring, in turn, is connected 40 with a clamp 13 which may be clamped to the side of the journal box by the tightening of a screw 14. Partition walls 15 and 16 having the connecting openings 17 and 18 formed through them prevent undue splashing of the water within the receptacle 5 and 45 consequently prevent this water from spilling out of the top of the receptacle under the swaying motion of the car.

50 A valve 19 leads from the lower part of the receptacle 5 and at that side of the receptacle toward the journal box. A screen 20 prevents the entry of dirt or other foreign particles to the valve 19 from the receptacle and consequently prevents the entry 55 of such dirt into the discharge pipe 21. This discharge pipe is connected with the

body of the valve by means of a sleeve 22 and the end of the pipe is provided with a rounded portion 23 of such a nature as to permit of the shifting of the position of the pipe to one side or the other of the journal. By mounting the receptacle in the position shown and opening the valve 19 to the proper degree, water from the receptacle 60 may be run continuously upon the heated journal and will cool the journal to a sufficient extent to permit of the car being carried to its destination. It will be observed that the receptacle 5 is supported directly 65 within the mouth of the journal box and this brings the receptacle in such proximity to the heated journal and journal box as to prevent the freezing of the water therein. A plate 24 secured to the bottom of the receptacle is provided with downturned 70 members 25 and 26. The members 25 abut against the outer edge of the mouth of the journal box and aid in supporting the receptacle in position, while these several projections together constitute legs for the receptacle.

It is to be understood that the invention is not limited to the precise construction set forth but that it includes within its purview whatever changes fairly come within either 80 the terms or the spirit of the appended claims.

Having described my invention what I claim is:

1. A device for cooling journals comprising a tank adapted to receive water, means for conducting water therefrom to a journal to be cooled and means for supporting the tank in the open mouth of a journal box, said means comprising a flexible element 90 adapted to embrace the tank, a clamp connected to said flexible element and adapted to embrace and grip a sidewall of the journal box to draw the tank toward the journal box and elements upon the bottom of the 95 tank engageable with the front edge of the journal box and limiting the inward movement of the tank.

2. A device for cooling heated journals comprising a tank, means for supporting the same in the open mouth of the journal box, a partition wall spanning the tank in one direction and having an opening therethrough near the lower end thereof, a second partition wall extending substantially at right 110 angles to the first named partition wall but not completely dividing that part of the

tank into which it projects into separate compartments, a valve leading from the lower portion of the tank, and a rigid pipe having swiveled connection with the casing of said valve, said pipe having an offset portion adapted to be swung to varying positions around the circumference of journal to be cooled.

3. A device of the character described comprising a tank and means for supporting the same in the open mouth of a journal box comprising members upon the bottom of the tank adapted to engage the lower front edge of the journal box, a chain adapted to

extend around the tank and a clamp to 15 which the ends of the chain are connected, said clamp having a bifurcated formation and adapted to embrace the sidewall of the journal box and having a toothed inner jaw and a clamping screw threaded to the outer 20 jaw.

In testimony whereof he affixes his signature in the presence of two witnesses.

ENNIS E. SHERRILL.
